J. GALAMBOS

SASH HOLDER

Filed Dec. 7, 1927

FIG. 1

FIG. 2

Inventor

John Galambos

By
Brockett & Hyde

Attorneys

UNITED STATES PATENT OFFICE.

JOHN GALAMBOS, OF CLEVELAND, OHIO.

SASH HOLDER.

Application filed December 7, 1927. Serial No. 238,392.

This invention relates to window sash holders and particularly to those used in connection with window sash which do not have window weights.

5 In many types of houses and other buildings it has become the practice to provide a window sash with means for holding it in any desired position without the use of counterbalance weights. This practice was 10 prevalent many years ago and is well known and understood, and is still occasionally necessary on account of the cost of building. Many of the devices used heretofore have been extremely ineffective in holding the sash 15 in any desired position and yet permitting it to be moved freely to closed position.

The object of the present invention therefore is to provide a holding device for a window sash which shall be simple in construction and certain in operation.

20 The exact nature of the invention will be apparent from the following description taken in connection with the accompanying drawings in which Fig. 1 is a sectional elevation 25 of pertinent parts of a window installation to which my device has been applied showing the device in elevation with portions cut away to show construction; Fig. 2 is a view of the device itself, looking from a different direction as from the right side of the device when positioned as in Fig. 1.

The principal member of the device is a base or frame 1 having a pair of side portions 2, a through opening 3 therebetween, 35 and end portions 4 drilled as indicated to receive screws by which the base may be secured when set into the recess 5 of the side members 6 of a window sash of which 7 represents the pane of glass.

40 Extending between the side portions 2 of the base is a pin 8 upon which is mounted between the side portions a lever 9. The lever has a long end upon which is formed a projection 10 opposite a similar projection 11 on the base; the projection serving to position a helical compression spring 12 whereby the lever 9 is yieldably urged in clockwise direction Fig. 1. The opposite end of the lever carries a pin 13 of sufficient length to overhang the side portions 2 of the base and thus limit spring urged movement of the lever 9 by bearing against the shoulder portions 14 of the base side portions. Upon the pin 13 is mounted a generally U-shaped rocker 15 having two side members carrying between

them the pin 16 and a connecting web portion 17. A roller 18 is mounted upon the pin 16. Motion of the rocker 15 upon the pin 13 is limited in clockwise direction Fig. 1, by engagement of the roller with the lever 60 9 as indicated, and in counter-clockwise direction, Fig. 1, by engagement by the web 17 with the lever.

When the parts are assembled as described the spring 12 will cause the roller 18 to be 65 urged outwardly of the face 19 of the base and sash. This outward movement however, being limited by the pin 13 abutting the shoulders 14 of the base.

Operation will be as follows assuming the 70 window sash to which the device has been applied has been mounted in a window frame of which the member 20 lies adjacent the member 6. The clearance between the members 6 and 20 of the sash and frame respectively is such that the roller which is preferably of non-metallic material such as fabric, will at all times be caused to bear against the member 20 by the spring 12. Assuming the window half way open, that is the sash slid 80 half way up, the parts are in the position shown. At this time the tendency of the sash is to slide downwards due to gravity but the bearing of the roller against the frame serves to move the rocker counter clockwise 85 about its pivot so that the roller bears also against the lever which has sufficient braking action upon the roller to prevent rotation thereof. The spring 12 is of sufficient strength and the friction of the roller material is such that the window is maintained in this position.

Should it be desired to raise the window further upward movement of the sash effects counter clockwise (Fig. 1) movement of the 90 rocker freeing the roller from the lever and therefore freeing the sash in the frame. To close, the sash is lowered, the roller sliding upon the frame member 20 with just sufficient friction to offset the force of gravity. 100

It will be noted that the roller is positively positioned through the mounting of its axis pin 16 in the rocker so that the tendency to jam due to misalignment of the roller is positively prevented. It will also be noted that the tilting motion of the rocker is limited by the means described to a small angle in which the arc travelled by the axis pin extends only slightly above and below the elevation, Fig. 1, of the pin 13; so that motion of the 110

roller is substantially independent of the angular position of the rocker, and therefore governed practically solely by the bearing of the roller against the frame member 20.

5. What I claim is:

1. In an article of the class described, a base adapted to be fitted to a window sash and having side portions, a lever movable on said base, a rocker, a pin connecting said lever and rocker whereby the latter is carried by the former, a roller mounted on said rocker, spring means arranged to yieldably urge said lever to maintain said roller bearing against the frame in which said sash slides, said rocker being arranged to move said roller to bear against said lever or to free the same therefrom, dependent upon relative movement of said sash and frame.
10. 2. In an article of the class described, a base adapted to be fitted to a window sash, a lever movable on said base, a rocker carried by said lever, a roller mounted on said rocker, spring means arranged to yieldably urge said lever to maintain said roller bearing against the frame in which said sash slides, said rocker being arranged to move said roller to bear against said lever or to free the same therefrom, dependent upon relative movement of said sash and frame, and having a web portion adapted to abut said lever to limit said roller freeing movement.

20. 25. 30.

In testimony whereof I hereby affix my signature.

JOHN GALAMBOS.
